UNITED STATES PATENT OFFICE.

ALBERT L. CRAIG, OF STANHOPE, IOWA.

GASOLENE-ENGINE.

1,360,895.

Specification of Letters Patent. Patented Nov. 30, 1920.

Application filed March 1, 1919. Serial No. 279,928.

To all whom it may concern:

Be it known that I, ALBERT L. CRAIG, a. citizen of the United States, residing at Stanhope, in the county of Hamilton and State of Iowa, have invented new and useful Improvements in Gasolene-Engines, of which the following is a specification.

This invention relates to internal combustion engines of the two-cycle type, one of the main objects of the invention being to do away with crank case compression and employ in lieu thereof novel and reliable means of a simple character by which full compression of the explosive mixture is brought about by the piston within the cylinder proper.

Another object in view is to eliminate as many working parts as possible, thus reducing the cost of production and maintenance of the engine and further adding to the reliability thereof in use.

To the above end, the invention consists in the novel construction, combination and arrangement, herein fully described, illustrated and claimed.

In the accompanying drawings:

Figure 1 is a diametrical section through the improved engine with the piston at the outer limit of its travel.

Fig. 2 is a similar section with the piston at the inner limit of its travel.

The cylinder 1 has a stepped bore, that portion 2 of the bore next to the crank shaft being of greater diameter than the remaining portion 3 of the bore which latter forms the combustion chamber. This arrangement provides an internal annular compression shoulder or wall 4 in the cylinder.

The piston 5 through the greater part of its external area fits the bore 3 of the cylinder and has a relatively narrow enlarged portion or compressing flange 6 which works in the larger bore 2 of the cylinder. The piston carries packing rings 7, 8 and 9 to prevent leakage.

Arranged within the skirt of the piston is a compression shell 10 which is held fixed by providing the same with a flange 11, clamped between the cylinder base and the crank case. The shell 10 forms the inner wall of the compression chamber 12, the latter being formed between the cylinder wall, the shell 10, the flange 11 the shoulder 4.

An intake 13 from a source of mixture supply such as a carburetor has branches 14 and 15 leading to the opposite ends of the

compression chamber 12, and said branches are controlled by inwardly opening check valves 16 and 17.

The cylinder wall is formed with a by-pass 18 of sufficient length to extend around the compressing flange 6 of the piston when at the outer limit of its travel (see Fig. 1) permitting the fluid to pass from the outer to the inner side of said flange. The inner terminus of the by-pass 18 is over run by the compression flange 6.

A main by-pass 19 leads from the inner end of the compression chamber 12 to the combustion chamber 20 of the cylinder and is controlled by a positively opened valve 21 operated at the proper time by a cam on the crank shaft.

The exhaust valve 22 is located in the cylinder head and positively operated by the well known push rod, rod and rocker arm means shown. The cylinder head has a hole 23 to receive a spark plug. The piston is coupled to its connecting rod 24 by a ball and socket joint 25, the latter being connected to the body of the piston by a spider or arms 26 between which are intervening spaces 27.

The operation of the engine is as follows: The piston in moving along its working stroke causes the flange 6 to suck explosive mixture into the compression chamber 12 through the intake branch 14. In the return stroke of the piston such mixture is compressed against the shoulder 4. During this stroke a fresh supply of explosive mixture is sucked into the compression chamber 12, through the intake branch 15. At the limit of this stroke the piston over runs the lower end of the by-pass 18 and the compressed mixture trapped between the flange 6 and shoulder 4 escapes through the by-pass 18 and enters the compression chamber on the opposite side of the flange 6 permitting it and any further supply of fuel mixture that has entered said chamber through the intake branch 15 to mingle, thereby tending to heat the same by reason of the previous compression of the initial charge.

During the next working stroke of the piston the combined mixture is compressed between the flange 6 and the base 11 of the compression shell 10. Then, as the piston approaches the limit of its inward travel it uncovers the main by-pass 19 and at the same time the valve 21 is positively opened

permitting the compressed charge to rush into the combustion chamber 20, forcing the burned gas past the exhaust valve 22 which is positively opened at such time. Ignition 5 occurs when the piston is approximately at the outer limit of its travel, in the position shown in Fig. 1. The operation just described is then repeated.

I claim:

- 10 1. A two cycle engine, comprising a cylinder having the crank shank end portion of its bore enlarged to form a suction and compression chamber, a piston fitting the smaller bore of the cylinder and having a compressing flange fitting the larger bore of the cylinder, a stationary compression shell fitting against the inner wall of the piston and forming the inner wall of said compression chamber, an intake from a source of fuel mixture supply leading to the opposite ends of the compression chamber, means for establishing and conducting the initially compressed fuel mixture in the compression chamber from one side of the compression flange to the other in said chamber for combining with a fresh fuel mixture supply for recompression, and means for conducting the full compressed charge of said fuel mixture from said compression chamber to the combustion chamber of the cylinder.
- 25 2. A two cycle engine, comprising a cylinder having the crank shank end portion of its bore enlarged to form a suction and compression chamber, an intake from a source

of fuel mixture supply leading to the opposite ends of the compression chamber, a piston fitting the smaller bore of the cylinder and having a compressing flange fitting the larger bore of the cylinder, a by-pass 40 for conducting compressed fluid from one side of said compressing flange to the other, which by-pass is overrun by said flange, a stationary compression shell fitting against the inner wall of the piston and forming the 45 inner wall of said compression chamber, and means for conducting compressed charges from said compression chamber to the combustion chamber of the cylinder.

3. A two cycle engine, comprising a cylinder having the crank shank end portion of its bore enlarged to form a suction and compression chamber, an intake from a source of fuel mixture supply leading to the opposite ends of the compression chamber, a piston fitting the smaller bore of the cylinder and having a compressing flange fitting the larger bore of the cylinder, a by-pass 55 for conducting compressed fluid from one side of said compressing flange to the other, which by-pass is overrun by said flange, a stationary compression shell fitting against the inner wall of the piston and forming the inner wall of said compression chamber, and a valve controlled by-pass for conducting compressed charges from the lower end of said compression chamber to the combustion chamber of the cylinder.

In testimony whereof I affix my signature.

ALBERT L. CRAIG.
